ATTORNEY

UNITED STATES PATENT OFFICE.

FREDERIC BARR, OF NEW YORK, N. Y.

ELECTRIC SWITCH.

1,112,882.

Specification of Letters Patent.

Patented Oct. 6, 1914.

Application filed April 21, 1911. Serial No. 622,526.

To all whom it may concern:

Be it known that I, FREDERIC BARR, a citizen of the United States, and resident of New York, in the county of Kings and State of New York, have invented certain new and useful Improvements in Electric Switches, of which the following is a specification.

My invention relates particularly to a chain guide construction for pull socket switches.

It has been customary in the past to provide a guide for the operating chain or cord and to fasten the guide to the shell in some cases and in other cases to the porcelain. Both of these constructions have disadvantages in manufacture, assembling and repair.

It is my object to avoid these difficulties and to provide a simple, inexpensive construction which can be readily assembled or taken apart.

Figure 1, is a front view of a socket embodying the construction of my invention. Fig. 2, is a side view, the shell being shown in section. Fig. 3, is a plan view, the cap of the shell being removed. Fig. 4, is a perspective view of the body of the shell showing the slot for receiving the chain guide. Fig. 5, is a perspective view of the chain guide. Fig. 6, is a horizontal section of another form of switch with the chain guide of my invention.

The socket shell consists of the body 1 and the cap part 2 which telescope with one another and may be provided with any suitable form of interlocking devices.

In the form of construction shown in Figs. 2 and 3 the switch parts are carried by the two porcelain members 3 and 4 and surrounded by insulating fiber 5.

The chain guide 6 has a central passage 7, an inner flange 8 and an outer flange 9 leaving an annular groove 10 between the flanges. The operating chain or cord 11 extends through the passage 7. The body 1 of the socket shell has a slot 12 in its upper edge to receive the chain guide, the flange 8 fitting on the inside of the shell and the flange 9 on the outside. When the cap 2 is on the body 1 the chain guide is held in place.

To prevent the main parts of the switch from turning in the shell I provide a lug 13 which is integral with the upper porcelain 4 and projects into the upper end of

the slot 12 in the body 1 of the shell. This lug is just long enough to project through the insulating fiber 5 and the thickness of the body of the shell. When the cap 2 is in place its lower edge covers the lug 13. This lug also helps to steady the chain guide by reinforcing the shell at this point. A groove 14 may be provided in the lower edge of the lug 13 to afford additional means for positioning the chain guide.

In the form of construction shown in Fig. 6 the switch spindle 20 is held in position by the body 21 of the shell so that relative displacement is prevented. Obviously the chain guide may be extended from the shell to any extent desired as shown for instance, in Fig. 6 where the bell portion 22 projects from the main part of the guide 23. This keeps the chain 24 farther away from the shell.

It will be obvious that the chain guide construction may be applied to any form of pull socket switch as it is wholly independent of the switch or the porcelain or other parts inside the shell.

What I claim is:

1. A pull socket comprising a shell body having a slot in its upper end, a double flanged eyelet detachably carried by said shell in said slot forming a chain guide and having its flanges overlapping the edges of the body surrounding the slot and a shell cap on the body holding the eyelet in place.

2. A pull socket comprising, a porcelain carrying the switch parts and having a lateral projection, a shell inclosing said parts and consisting of a body and a cap, said body having a slot receiving said projection, a chain guide detachably fitted in said slot and having a flange on its inner end beneath said projection, said cap covering said projection.

3. In a pull socket, a metallic shell-body having a slot, a chain guide having a groove removably fitting the edges of the metal around the slot and a shell-cap fitting the edge of the body and holding the chain guide in place.

4. In a pull socket, a metallic shell-body having a slot, a chain guide having a groove removably fitting the edges of the metal around the slot, a shell-cap fitting the edge of the body and holding the chain guide in place and a porcelain inside the shell having a projection for preventing relative displacement.

5. In electric light pull sockets the combination of a shell provided with a slot, a removable chain guide having means to co-operate with the walls of the slot, a cap to prevent the movement of the chain guide in one direction, and means for securing the cap and shell together.

6. In an electric pull socket, a shell consisting of a body having an open slot at one end and a cap fitting over said end and a removable chain guide fitted in said slot and having flanges embracing the inner and outer walls of said body and cap.

7. In electric light pull sockets, the combination of a shell provided with a slot, a removable chain guide mounted in the slot, a socket body, means to accurately position the socket body in the shell in relation to the slot for the removable chain guide, and a cap to secure the chain guide from movement in one direction. 15 20
